ABSTRACT: The piston has a lowermost ring-receiving groove formed adjacent the inner end of its bottom side with an annular oil-receiving trough. Oil removed from the cylinder wall by the piston ring during the down stroke of the piston is directed into the trough. A series of vertically extended circumferentially spaced holes in the trough function as drain holes for conveying the oil from the trough to the interior of the piston in response to the change in the directional travel of the piston on the completion of its downstroke travel.

PISTON FOR AN INTERNAL COMBUSTION ENGINE

SUMMARY OF THE INVENTION

The piston embodies a built-in oil control device that is readily adapted to commercially available pistons. The usual oil ring functions during the downstroke of the piston to remove excess oil from the cylinder wall and to direct such oil into the receiving trough of the oil ring groove. On a reversal of the piston travel to commence its upstroke the oil collected in the trough is ejected therefrom through drain holes vertically extended through the trough bottom and open to the interior of the piston. The trough is thus emptied of oil during each upstroke travel of the piston and receives oil during each downstroke travel of the piston. Excess oil is thus positively and continuously removed from the cylinder wall for return to the engine crankcase without reliance on piston blowby for such purpose.

BRIEF DESCRIPTION OF THE DRAWINGS

FIG. 1 is a side elevational view of the piston of this invention with parts broken away and shown in section to more clearly illustrate its construction;

FIG. 2 is a sectional view of the piston taken along the line 2-2 in FIG. 1;

FIG. 3 is an enlarged sectional detail view of the head section of the piston showing the collection of excess oil from the cylinder wall on the downstroke travel of the piston; and

FIG. 4 is illustrated similarly to FIG. 3 and shows the discharge of the collected oil to the interior of the piston during its upstroke travel.

DETAILED DESCRIPTION OF THE PREFERRED EMBODIMENT

With reference to FIG. 1, the piston of this invention, indicated generally at 10, has a head 11, a depending generally cylindrical skirt 12 and pin bosses 13 projected laterally inwardly of the piston from diametrically opposite sides of the skirt 12. The junction of the head 11 with the skirt 12 is defined by an annular radially extended shoulder 14 that extends about the inner periphery of the skirt.

The head 11 has a plurality of axially spaced piston ring grooves, illustrated as three in number, that extend peripherally around the ring belt area of the head 11. The upper grooves 16 are provided with compression rings 17 and the lowermost groove 18 with an oil ring 19 of a usual type having top and bottom oil ring rails 20 and 21, respectively.

The groove 18 has a lower side 22 and an inner base side 23 (FIGS. 2 and 3). Formed in the lower side 22 with one wall continuous with the groove base side 23 is an annular oil-receiving trough 24 which has a width substantially equal to about one-half the radial depth of the groove 18. The depth of the trough 24 is equal to about one-half of its width. Circumferentially spaced about the trough 24 and formed in the bottom thereof are drain holes 26 which extend vertically downward through the head 11 and open into the interior of the piston at the shoulder 14.

In the operation of the piston 10, let it be assumed that the piston is in its downstroke travel shown in FIG. 3. During this travel the lower rail 22 of the oil ring 19 is moved upwardly to a slightly spaced position above the groove bottom wall 22 by the engagement of the outer peripheral surface of the ring rails 20 and 21 with the inner peripheral surface of the associated cylinder wall 27. Excess oil on the surface of the cylinder wall is removed or scraped therefrom by the lower ring rail 21 and directed thereby into the trough 24 through the space formed between the groove bottom side 22 and the ring rail 21. This directing of oil from the surface of the cylinder wall 27 into the trough 24 continues during the full downstroke travel of the piston 10.

As the piston 10 starts its upstroke travel, as shown in FIG. 4, the oil within the trough 24 is whipped outwardly from the trough through the drain openings 26 and into the interior of the piston 10 for return to the engine crankcase (not shown). This discharge flow of oil from the trough 24 continues over approximately the initial two-thirds of the upstroke travel of the piston 10 due to the acceleration of the piston speed during such travel.

Excess oil from the cylinder wall 27 is thus positively and continuously removed for return to the engine crankcase without reliance on the usual blowby through the rings 17 and 19 for such purpose. With the use of rings 17 having a mitered split, as shown in U.S. Pat. No. 2,569,777, piston blowby may be substantially eliminated and a desired lubrication condition obtained by varying the number and size of drain openings 26. By utilization of such controlled oil flow concurrently with the substantial elimination of piston blowby, the piston 10 is more efficiently cooled and engine efficiency is improved due to the maintenance of more uniform compression pressures in the engine cylinders and the reduction of carbon formation in the cylinder combustion chambers.

I claim:

1. A piston assembly for the cylinder of an internal combustion engine, comprising:
  - a head section formed with a series of axially spaced peripheral ring-receiving grooves;
  - the lowermost one of said grooves formed in the lower sidewall thereof with an annular oil-receiving trough having an inner sidewall lying substantially in the plane of the base of said lowermost groove, and a bottom wall having a series of circumferentially spaced vertically extended holes connecting said trough in fluid registration with the interior of said piston, said trough having a width equal to at least one-half the radial depth of said lowermost groove;
  - an oil ring for said lowermost groove having an outer peripheral surface in bearing engagement with the wall of said cylinder; and
  - said oil ring, during the downstroke travel of the piston within said cylinder, acting to remove and direct oil from the wall of said cylinder along the lower side of said lowermost groove and into said trough, with the oil in the zone of said holes being discharged through said holes and into the interior of said piston during the accelerated upstroke travel of the piston.
